UNITED STATES PATENT OFFICE.

JOHN C. BEDINGFIELD, OF CARL, GEORGIA, ASSIGNOR OF ONE-HALF TO E. L. WILLIAMSON, OF JEFFERSON, GEORGIA.

PACKAGE-TIE.

1,312,015.

Specification of Letters Patent.

Patented Aug. 5, 1919.

Application filed July 14, 1917, Serial No. 180,677. Renewed March 5, 1919. Serial No. 280,818.

To all whom it may concern:

Be it known that I, JOHN C. BEDINGFIELD, a citizen of the United States, residing in Carl, in the county of Barrow and State of Georgia, have invented a new and useful Package-Tie, of which the following is a specification, reference being had to the accompanying drawing, forming a part hereof.

The object of the invention is to provide a package tie embodying a cord or similar flexible element and a means designed to be permanently attached to one end of the cord, and constructed to have the other end of the cord detachably engaged therewith, such device being specially designed for packaging or bundling mail matter so that it may be readily handled in transportation and filing; and a special object of the invention is to provide a tie of such construction as not only to facilitate the tying operation, but to enable the bundle to be untied instantly and by a single movement of the operator, without the risk of the entanglement of the cord, with due regard to the efficiency of the tie when the bundle has been formed, so that rough usage or handling of the bundle may not result in the loosening of the tie.

Further objects and advantages of the invention will appear in the course of the following description, it being understood that changes in form, proportion and minor details, may be resorted to without departing from the spirit of the invention.

In the drawing,

Figure 1 is a perspective view of a tie embodying the invention applied in the operative position to a bundle of letter envelopes or the like.

Fig. 2 is a plan view of the tie.

Fig. 3 is a side or edge view of the same.

Figs. 4, 5 and 6 are similar views of a modified construction of tie.

The tie embodying the invention consists essentially of a plurality of co-acting jaws, 10 and 11, each consisting of or provided with a plurality of ribs which are adapted to intermesh or occupy intercurrent relations, and as illustrated, the jaw 10 consisting of a base plate 12 having the longitudinally disposed ribs 13, while the jaw 11 consists of a plurality of strands 14 which may be constructed continuously with the ribs 13, or of a single length of wire doubled upon itself, the portion 13 being soldered or brazed or otherwise secured to the plate 12,

which is adapted to be attached to one end of the bundling cord 15. If the jaws are constructed of a single folded length of wire, as illustrated in the drawing, one end of the wire blank is secured to the base plate, or to the other portions of the blank at or near to the throat formed by the jaws, while the other end of the blank is secured by solder or otherwise to the arch of the loop forming the yieldable jaw as shown in Figs. 1 and 2.

At the throat or closed end of the jaw construction, as shown at 16, the wire blank is secured to the plate with the intercurrent elements thereof in a common plane parallel with said plate whereby as the cord, 60 after having been passed (for example) longitudinally around the bundle may be drawn over the outwardly deflected free end of the jaw 11, or between the jaw members and advanced toward the throat 16, so that said 65 cord is crimped by passing under and over the intercurrent elements of the jaws to firmly clamp the same against accidental displacement. The cord may then be wrapped one or more times transversely 70 around the bundle, the number of times being dependent upon the size of the bundle, as it is the object to apply the cord to the bundle in such a way as not to leave any great length of free end of the cord projecting, and the free end of the cord, then passed over and then back under the outer or deflected jaw so as to firmly lock said free end 75 in position.

This operation having been accomplished, 80 the bundle may be tossed into an awaiting sack or other receptacle for transportation to the point of destination.

One of the most important features of the invention, as embodied in the foregoing disclosure resides in the fact that in applying the tie to a bundle of letters or similar objects, it is necessary simply to grasp the bundle with the thumb of the grasping hand of the operator resting upon the throat 95 end of the base plate while, by means of the other hand the end of the cord extending from its point of permanent attachment to one end of the base plate, is carried longitudinally around the bundle and passed under the free jaw where it may be drawn toward the throat sufficiently to secure a firm engagement. The necessary number of transverse wraps of cord may then be made and the extremity of the cord locked under 100 105 110

the outer jaw, to be crimped and engaged as above explained, by the intercurrent relations of the ribs. It is obvious that this operation can be carried out with a minimum expenditure of time, and without the relaxing of the bundle by the grasping hand until such operation has been completed.

The most important advantage of the construction described, however, resides in the fact that when it is desired to untie the bundle, it is necessary, merely, to grasp the bundle as before, with the thumb of one hand bearing upon the throat portion of the plate and grasp the free end of the cord with the other hand and draw straight out longitudinally of the tie in the direction indicated by the dart in Fig. 1. A steady strong pull of the cord terminal in said direction will entirely disengage the cord from the tie and at the same time unwrap it from the bundle, so that the elements of the latter are free for distribution.

After the cord has been applied and wrapped in accordance with directions, there is no possibility of an entanglement thereof, in the release of the bundle, by a single movement of the operator as explained.

The upward or outward flaring or deflection of the outer jaw, which is designed to facilitate the introduction of a cord wrap between the jaws, provides the outer jaw with a concaved or inclined back constituting a seat for the reception of the cord wrapped transversely around the bundle, and obviously such transverse wraps serve to increase the pressure of the outer jaw toward the base plate, and thus increase the firmness of the engagement of the jaws with the interposed cord.

The modified construction illustrated in Figs. 4, 5 and 6 embodies the essential elements hereinbefore described, in that it includes a ribbed base or lower jaw consisting of wire strands, 17, intermediate strands, 18, which may as shown be formed in a continuous length with the looped strands, 19, forming the co-operating jaw, the wire blank being extended beyond the mouth of the jaw to form a cord attaching loop, 20. The intermediate strands of the base or lower jaw may be arched or deflected upwardly from the plane of the strands, 17, to lie between the strands of the loop forming the upper or yielding jaw, so that an effective crimping of the tie cord, 21, may be secured, the method of applying and using the tie being the same as that hereinbefore described with reference to the form of the device illustrated in Figs. 1 to 3 inclusive.

Having now described the invention what is claimed is:

1. A package tie having a cord engaging member consisting of a base for contact with a bundle and a co-acting yielding jaw, between which and the base the cord may be

engaged, said jaw having a back or outer surface forming a seat for transverse cord wraps, the base consisting of a plate and the jaw consisting of spaced longitudinal wire strands for yielding movement toward and from the plate and adapted to be held depressed by the transverse cord wraps.

2. A package tie having a cord engaging member consisting of a base to bear upon a bundle and a co-acting yielding jaw, between which and the base the cord may be engaged, and having a back forming a seat for transverse cord wraps for forcible depression of the jaw, the base consisting of a plate having longitudinal ribs, and the jaw having longitudinal ribs disposed intercurrently with those on the base.

3. A package tie having a cord engaging member consisting of a base and a co-acting yielding jaw, between which and the base the cord may be engaged, and having a back forming an intermediately depressed seat for transverse cord wraps, the base consisting of a plate to bear upon a bundle and having longitudinal ribs on its outer surface and the jaw consisting of spaced longitudinal wire strands disposed intercurrently with the base ribs and normally arranged in a common plane therewith.

4. A package tie having a cord engaging member consisting of a base to bear on a bundle and a co-acting yielding jaw, between which and the base the cord may be engaged, and said jaw having a back forming a seat for transverse cord wraps, the base consisting of a plate having longitudinal ribs, and the jaw consisting of spaced longitudinal wire strands disposed intercurrently with and respectively outside of and between the base ribs, said base ribs and jaw strands comprising a continuous length of wire of which said rib portions are secured to the surface of plate.

5. A package tie having a cord engaging member consisting of a base and a co-acting yielding jaw, between which and the base the cord may be engaged, said base and jaw consisting of a plurality of intercurrently arranged wire strands normally disposed substantially in a common plane, the base having an intermediate strand and the jaw consisting of a loop between the sides of which said intermediate strand is located, the intermediate strand being arched.

6. A package tie having a cord engaging member consisting of yieldingly related jaws one of which constitutes a base which is substantially flat and is adapted for contact with the surface of a bundle to be tied and is provided with terminal means for the attachment of a wrapping cord, each of said jaws consisting of a plurality of wire strands extending longitudinally of the jaws, the strands of one jaw being disposed intercurrently with relation to those of the

other jaw and normally disposed substantially throughout their lengths in a common plane, and the other jaw, which is yieldingly movable toward and from the 5 jaw forming the base, having an outwardly deflected free-end forming a concaved back adapted to provide a seat for cord wraps extending around a bundle in a plane transverse to the length of the jaw, to secure the

second named jaw in a fixed relation with 10 the jaw forming the base.

This specification signed and witnessed this 13 day of June A. D., 1917.

JOHN C. BEDINGFIELD.
